UNITED STATES PATENT OFFICE.

CLARENCE E. PAYNE, OF EMPIRE, COLORADO.

ORE-GRINDING MACHINE.

Application filed May 5, 1927. Serial No. 188,993.

The present invention relates to a machine for finely grinding ore or any other elements and has for its principal object to provide a centrifugal structure for casting the ore against liners for crushing the ore so that the same may drop perpendicularly down on another set of grinding elements of similar construction.

A still further important object of the invention lies in the provision of a machine of this nature which will not clog up and in which the centrifugal casting member functions as a flywheel and allows the machine to operate with a minimum amount of energy.

A still further very important object of the invention lies in the provision of a grinding machine of this nature with an exceedingly simple construction that is strong and durable, thoroughly efficient and reliable in operation, inexpensive to manufacture, and one in which the parts are accessible by means easy to assemble and disassemble and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a vertical sectional view through the machine embodying the features of my invention.

Figure 2 is a top plan view of the revolving casting member.

Figure 3 is an enlarged detail section taken substantially on the line 3-3 of Figure 2.

Figure 4 is a sectional elevation of the machine, and

Figure 5 is a top plan view of the hopper.

Referring to the drawing in detail it will be seen that the numeral 5 denotes a plurality of legs on which is supported an outlet hopper 6 of an inverted frusto-conical for-

mation having an annular flange at the top thereof indicated by the numeral 7 and resting on the upper ends of the legs 5. The legs 5 may be supported on a concrete foundation or the like. A casing is disposed above the outlet hopper 6 and is of a stepped formation decreasing in diameter from the bottom to the top. The bottom section of the casing comprises a ring 8 having an outwardly disposed flange at its lower end as at 9 and a similar flange 10 at its upper edge and at said upper edge is further provided with inwardly directed flange 11. Flanges 7 and 9 are bolted or otherwise secured as at 12 to the legs 5. The next section comprises an annular ring 14 smaller in diameter than the ring 8 and having at its lower edge an outwardly directed flange 15 resting on flanges 10 and 11 and bolted to flange 10 as at 16 and at its upper edge is provided with an outwardly directed flange 17 and an inwardly directed flange 18. Top casing section is formed by a ring 19 having a flange 20 at its lower edge directed outwardly and bolted to flange 17 as at 21 and formed at its upper edge with an inwardly directed flange 22 which merges into an inlet hopper structure 23. The numeral 24 denotes a conical shaped member formed with annular flanges 25, 26 and 27 directed outwardly therefrom and disposed respectively in sections 8, 14 and 19 of the casing and decreasing upwardly in diameter as said casing sections.

On each of the flanges 25, 26, 27, there is formed a plurality of radiating ribs 28 which rise therefrom and which have bolted thereto wear blocks 29 as is indicated to advantage in Figure 3. Each wear block 29 has a concave surface for engaging the ore or the like as will be more apparent later. This member 24 is keyed on a shaft 30, the upper end of which is journaled in a cross head 31 extending through openings 32 in the inlet hopper 23 and having a shield 34 thereover, said shield and said cross head being securely fastened as at 35 to projections 36 on the hopper 23. Suitable anti-friction bearings 37 are provided in the

cross head to allow free rotation of the shaft, The lower end of the shaft is journaled in a casing 38 having anti-friction bearings 39 therein. This casing 38 extends across the outlet hopper structure 6 as is clearly shown in Figure 4. On the shaft within the casing 38 is a belt pulley 40 for driving the pulley and the shaft. The lower portion of the casing is open and is closed by a removable plate 41.

When the member 24 is revolving in a clockwise direction as shown in Figure 2, and ore or like material is poured into the inlet hopper 23 said material will be cast outwardly by the wear blocks 29 against liners 43 on the interior of the casing sections for crushing the ore and allowing the same to drop perpendicularly into the next section. Thus the ore will be finely ground and there will be very little likelihood of the machine becoming clogged up because of the vertical drop of the material from one section to the other and because of the centrifugal force which will cast the material against the liners. The machine will use little energy in its operation because of the flywheel action of the member 24 after the same has been started. It will be seen that because of the sectional construction of the casing the various parts are readily accessible and the various parts may be assembled and disassembled with ease. It will also be seen that practically all the wear is taken up by the wear blocks 29 and the liners 43 and that these are the only parts which will have to be replaced under ordinary circumstances during the life of the machine.

It is thought that the construction, operation, and advantages of this invention will now be clearly understood without a more detailed description thereof. It is important to bear in mind that the cone shaped member 24 enables the increasing diameter of the different sections and thus the ore or pulp drops perpendicularly from one chamber to the other and particular attention is directed to the fact that said ore or pulp always drops into a larger chamber because of the increasing area of the chambers from the top to the bottom which is provided by the increased diameter of the casing sections and the corresponding increasing diameter of the flanges on the cone-shaped member. It is also to be noted that the changes formed by the sections are in close proximity to each other thus eliminating pockets or unnecessary space above or below the casting elements formed by the wear blocks. The shaft is adapted to revolve at a high rate of speed and thus the pulp is caused to be held in suspension thus eliminating any chance of clogging. It is also to be noted that the number of casting elements increases as the diameter of the casing sections increase.

The present embodiment of the invention has been disclosed in detail merely by way of example since in actual practice it attains the features of advantage enumerated as desirable in the statement of the invention and the above description. It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. A machine of the class described comprising a stepped casing forming a plurality of chambers increasing in diameter from top to bottom, a cone-shaped member, means for mounting the cone-shaped member in the casing, a plurality of flanges of annular formation projecting outwardly from the cone-shaped member one in each chamber, a plurality of radially disposed ribs on the flanges projecting upwardly therefrom, wear blocks fixed to said ribs. 90

2. A machine of the class described comprising a stepped casing forming a plurality of chambers increasing in diameter from top to bottom, a cone-shaped member, means for mounting the cone-shaped member in the casing, a plurality of flanges of annular formation projecting outwardly from the cone-shaped member one in each chamber, a plurality of radially disposed ribs on the flanges projecting upwardly therefrom, wear blocks fixed to said ribs, each wear block having its abutting surface of a concave formation. 95 100

3. A machine of the class described comprising a stepped casing forming a plurality of chambers increasing in diameter from top to bottom, a cone-shaped member, means for mounting the cone-shaped member in the casing, a plurality of flanges of annular formation projecting outwardly from the cone-shaped member one in each chamber, a plurality of radially disposed ribs on the flanges projecting upwardly therefrom, wear blocks fixed to said ribs, each wear block having its abutting surface of a concave formation, said ribs and wear blocks increasing in number on the flanges from top to bottom. 110 115

4. A machine of the class described comprising a stepped casing forming a plurality of chambers increasing in diameter from top to bottom, a cone-shaped member, means for mounting the cone-shaped member in the casing, a plurality of flanges of annular formation projecting outwardly from the cone-shaped member one in each chamber, a plurality of radially disposed ribs on the flanges projecting upwardly therefrom, wear blocks fixed to said ribs, each wear block having its abutting surface of a concave for- 120 125 130

mation, said ribs and wear blocks increasing in number on the flanges from top to bottom, liners disposed in the chambers against which the material is cast by the wear blocks.

5. A machine of the class described comprising a casing, tapering vertically in order to be smaller in width at the top than at the bottom, a cone-shaped member, means for rotatably mounting the cone-shaped mem-

ber for rotation in the casing, a plurality 10 of flanges of annular formation projecting outwardly from the cone-shaped member in spaced relation to each other, a plurality of radially disposed ribs on the flanges projecting outwardly therefrom, and wear 15 blocks fixed to said ribs.

In testimony whereof I affix my signature.
CLARENCE E. PAYNE.
